UNITED STATES PATENT OFFICE.

JOSEPH VAN DUZER, OF FIRTHCLIFFE, NEW YORK.

CLOTHES-HANGING APPARATUS.

Application filed June 6, 1924. Serial No. 718,328.

This invention relates to improvements in clothes hanging apparatus, and has for one of its objects to provide a simple and improved apparatus by means of which clothes 5 may be hung outdoors on a line without necessitating a person leaving the house.

Another object is to so construct and mount the apparatus in the wall of a room that when said apparatus is not being used 10 it can be conveniently moved to an inoperative position and when in such position cold air will be effectively excluded from the room.

The above and other objects will appear 15 more clearly from the following detailed description, when taken in connection with the accompanying drawing, which illustrates a preferred embodiment of the inventive idea.

In the drawing—

20 Figure 1 is a fragmentary perspective view of the apparatus constructed in accordance with the invention and shown in its operative position;

25 Figure 2 is a similar view of the apparatus shown in its inoperative position;

Figure 3 is a view partly in section and partly in front elevation, the section being taken substantially on the line 3—3 of Figure 1, and the outer closure of the apparatus 30 being shown in its operative or closing position;

Figure 4 is a sectional view taken on the line 4—4 of Figure 3; and

Figure 5 is a section on the line 5—5 of 35 Figure 3.

The apparatus of the present invention is capable of being mounted in a wall 6 of a room and is provided therein with an opening 7 in which is fitted the casing 8 of the 40 apparatus. This casing is made of a size suitable to permit clothes which have been hung upon a line to pass therethrough and has its outer portion projecting beyond the exterior of the wall and its inner portion 45 provided with a flange 9 engageable with the inner surface of the wall to form a seal about the edge of the opening 7. The bottom of the casing 8 is preferably inclined downwardly and outwardly, as best shown in Figure 4, so that the casing will effectively drain in the event that rain or snow should enter the outer end thereof.

The casing is provided with an outer removable closure 10 which, when in position, 50 is mounted intermediate the inner and outer ends of the casing and abuts against the

bead 11 extending about the inner wall of the casing. The closure 10 carries a pivoted latch 12 the ends of which are capable of being swung into recesses 13 formed in 60 the side walls of the casing 8 so as to effectively retain the closure in its operative position. By swinging the latch 12 so as to disengage the same from the recesses 13 it will be obvious that the closure 10 may be 65 withdrawn into a room when it is desired to use the apparatus. An inner closure 14 in the form of a door is hinged at 15 to the casing and is capable of being swung to the position shown in Figure 2 to form a further closure for the inner end of the casing and may be held in such position by a hook 16 carried by the casing and engageable with an eye 17 secured to the adjacent edge of 70 the door.

Hinged at 18 to the top of the casing and at the inner end thereof is a supporting arm 19 capable of being swung to a vertical position when not in use, as shown in Figure 2, and to a horizontal inwardly extending 80 position, as illustrated in Figure 1, in which latter position said arm is supported by a flexible element 20, such as a chain, one end of which is connected to the free end of the arm and the other end to the wall 6 85 above the casing. When the arm 19 is in inoperative position a hook 21 may be employed to engage an eye 22 adjacent the free end of the arm. The free end of the arm 19 supports a suitable pulley 23 about 90 which extends the clothesline 24 which is projected through the casing 8 and connected at any desired distance from the house with another pulley similar to the pulley 23 which may be carried by a post or standard. 95

When the clothesline is in its operative position considerable slack in the line usually exists which will permit of the arm 19 being swung to its inoperative position and in so doing the line will be drawn taut. In order 100 that the line will not interfere with the complete closing of the closure 14 the upper end of the casing is provided with a notch 25 in which the clothesline 24 will engage, as shown in Figure 2. After the arm 19 has 105 been swung to its inoperative position the closure 10 may be placed in closing position and, as shown in Figures 3 and 4, said closure is of such a length as to provide a small space between the upper end thereof and 110 the top of the casing 8 for receiving the clothesline 24.

With the closure 10 in position and the door 14 closed, it will be obvious that air from the outside of the house will be effectively prevented from entering through the casing and that when the apparatus is in operation a person may conveniently hang clothes upon the line 24 and then pass the same through the casing 8 to be hung outdoors without leaving the room. Likewise, it will be obvious that when it is desired to remove the clothes from the line the same may be drawn through the casing into the interior of the room.

What is claimed is:

15. In a clothes hanging apparatus, a casing

capable of being mounted in the wall of a room, a clothesline supporting arm hingedly connected to said casing and movable to horizontal and vertical positions with respect thereto within the room and capable of supporting a clothesline which is extended through said casing, and a closure for the inner end of the casing, said casing having a notch in its upper inner face for receiving the clothesline when the supporting arm is swung to the vertical position whereby said line will not interfere with the complete closing of said closure.

JOSEPH VAN DUZER.
